CLAIM

The ornamental design for an in-vehicle display with mount as shown and described.

DESCRIPTION

FIG. 1 is a perspective view of an in-vehicle display with mount showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the in-vehicle display with mount where the in-vehicle display with mount is in a configuration of use.

The short-dash broken lines immediately adjacent to the shaded areas represent boundaries of the claimed design. In FIG. 9, the long-dash broken lines showing a car dashboard illustrate unclaimed environment. All other short-dash broken lines illustrate portions of the in-vehicle display with mount that form no part of the claimed design.
